CLAIM

The ornamental design for a combined toy rocket and launcher, as shown and described.

DESCRIPTION

FIG. 1 is a perspective of a combined toy rocket and launcher showing my new design;

FIG. 2 is a front elevation of the rocket, shown separately for clarity of illustration, the rear and side elevations being identical;

FIG. 3 is a bottom plan view of FIG. 2;

FIG. 4 is a top plan view of FIG. 2;

FIG. 5 is a front elevation of the launcher, shown separately for clarity of illustration, the rear elevation being a mirror image;

FIG. 6 is a left side elevation of FIG. 5, the hose having been removed for clarity of illustration;

FIG. 7 is a right side elevation of FIG. 6; and,

FIG. 8 is a top plan view of FIG. 5, the opposite side elevation being identical.

FIG. 1

FIG. 2

FIG. 3

FIG. 4
